UNITED STATES PATENT OFFICE.

THEODORE W. FOSTER, OF PROVIDENCE, RHODE ISLAND.

DESIGN FOR A HANDLE FOR BUTTON-HOOKS, PAPER-CUTTERS, OR SIMILAR ARTICLES.

SPECIFICATION forming part of Design No. 36,010, dated August 19, 1902.

Application filed June 30, 1902. Serial No. 113,881. Term of patent 7 years.

To all whom it may concern:

Be it known that I, THEODORE W. FOSTER, a citizen of the United States, residing at Providence, in the county of Providence and State of Rhode Island, have invented and produced a new, original, and ornamental Design for the Handle of a Button-Hook, Paper-Cutter, or Similar Article, of which the following is a specification, reference being had to the accompanying drawings, forming part thereof.

Figure 1 is a side view of the handle of a button-hook, showing my design, the blade of a paper-cutter being indicated in broken lines. Fig. 2 is a transverse sectional view taken through the broadest portion of the handle.

As shown in the drawings, my design consists of the raised representation of a male and female figure sitting in a swing suspended from the inwardly-curved foliation forming the margin of the upper end of the handle. Tropical leaves form the margins of the wave-

like outlines of the lower part of the handle, and tropical plants fill the space below the swinging figures. A foliated ferrule forms the junction of the handle with the stem of the button-hook. The whole presents to the eye the appearance of two persons sitting in a swing surrounded by tropical growth.

Having described my invention, what I claim as new, and desire to secure by Letters Patent, is—

The ornamental design for the handle of a button-hook, paper-cutter or similar article, as herein shown and described.

In testimony whereof I have signed my name to this specification in the presence of two subscribing witnesses.

THEODORE W. FOSTER.
